United States Patent Office

Des. 185,728
Patented July 21, 1959

185,728

SCHOOL EMBLEM

Charles A. Young, Philadelphia, Pa.

Application October 22, 1958, Serial No. 53,091

Term of patent 14 years

(Cl. D29—2)

FIG. 1

The dominant features of my design reside in the portions shown in full line.

I claim:

The ornamental design for a school emblem, as shown and described.
